UNITED STATES PATENT OFFICE.

ARVINE SHEPARD, OF DUNCAN, OKLAHOMA.

PISTON-GROOVE CLEANER.

Application filed May 7, 1920. Serial No. 379,580.

To all whom it may concern:

Be it known that I, ARVINE SHEPARD, a citizen of the United States, residing at Duncan, in the county of Stephens and State 5 of Oklahoma, have invented certain new and useful Improvements in Piston-Groove Cleaners, of which the following is a specification.

The packing ring grooves of internal combustion engine pistons require cleaning to remove carbon, soot and other accumulations which tend to foul them. This generally necessitates the removal of the packing rings which consumes time and frequently 15 results in the breaking of the packing.

The present invention provides a tool whereby the work may be easily, quickly and effectively performed without necessitating the removal of the packing from the grooves 20 provided the rings are of the ordinary split type, since the bit may be introduced into the piston grooves between the ends of the ring bordering upon the split.

The drawing illustrates a preferred embodiment of the invention. However, it is to be understood that in adapting the same to meet different conditions, various changes in the form, proportion and minor details of construction may be resorted to without 25 departing from the nature of the invention as claimed hereinafter.

In the drawing herewith attached,

Fig. 1 is a plan view of a tool embodying the invention, showing the same applied to 30 a piston, the latter being illustrated in end elevation, parts of the piston and tool being broken away,

Fig. 2 is a side view of the tool, and

Fig. 3 is a sectional detail on the line 40 3—3 of Fig. 1.

Corresponding and like parts are referred to in the following description and indicated in the several views of the drawing by like reference characters.

The body of the tool comprises a band 1 and handles 2. These parts constitute portions of a strip of metal of suitable length bent into the form substantially shown. The part 1 of the tool body is provided with one 45 or more bits 3 which are of a size to snugly fit the piston groove 4 to be cleaned. As shown most clearly in Figs. 1 and 3, the bit comprises a threaded shank which passes through an opening formed in the part 1 and receives a nut 5 by means of which the 50 bit is secured to the body. In constructing

the tool a strip of spring metal such as steel of suitable length is provided and the same is doubled upon itself and formed into circular outline to provide the band 1 which is 60 of a diameter corresponding to the diameter of the piston for which the tool is constructed. The end portions of the strip project in the same direction and constitute the handles. While it is contemplated to apply a 65 number of bits to the part 1 of the tool, nevertheless the part 1 may be supplied with a single bit thereby enabling the tool to be effectively used without necessitating removal of the piston ring from the groove of 70 the piston. When it is desired to use the tool without removing the ring from the groove, the tool is applied so that the bit 3 passes through the split of the piston ring. After the tool has been adjusted, the handles 75 2 are grasped and the tool rotated to cause the bit to pass completely around the groove thereby clearing the same of all carbon and other matter tending to foul the same. When the tool is used and the piston ring is re- 80 moved from its groove the part 1 may be provided with any number of bits, the tool being adjusted so that the bits enter the piston groove. In this case it is not necessary to completely rotate the tool because the bits 85 will tend to have an overlapping action.

I claim:

1. A piston groove cleaning tool comprising a resilient, curved scraper carrying member adapted to partly encompass a piston, a 90 scraper mounted on said carrying member and normally urged inwardly by the resiliency thereof, and the ends of said member being spaced apart and extended to form operating handles.

2. A ring groove cleaning tool comprising an expandable ring adapted to partly encompass a piston and an inwardly extending rectangular scraper on said ring, said scraper having three scraping edges adapted to contact with the bottom and side walls of the groove with the corners of the scraper extending into the corners of the groove, and manual means for compressing the expandable ring so as to hold the scraper within the 105 ring groove.

In testimony whereof I affix my signature in presence of two witnesses.

ARVINE SHEPARD.
